Otto.

UNITED STATES PATENT OFFICE.

HARRY E. DOERR, OF ST. LOUIS, MISSOURI, ASSIGNOR TO SCULLIN STEEL COMPANY,
OF ST. LOUIS, MISSOURI, A CORPORATION OF MISSOURI.

PEDESTAL-TRUCK SIDE FRAME.

1,356,700.

Specification of Letters Patent. Patented Oct. 26, 1920.

Application filed December 29, 1919. Serial No. 347,976.

To all whom it may concern:

Be it known that I, HARRY E. DOERR, a citizen of the United States, residing at St. Louis, in the county of St. Louis and State 5 of Missouri, have invented certain new and useful Improvements in Pedestal-Truck Side Frames, of which the following is a specification.

This invention relates to pedestal truck 10 side frames.

Heretofore pedestal truck side frames have required a special journal box. Accordingly, such a side frame could not be used for replacements of arch bars or the 15 standard type of frame, both of which use Master Car Builders' journal boxes.

Therefore, one object of this invention is to provide a simple and novel pedestal truck side frame which will accommodate 20 Master Car Builders' journal boxes.

Another object is to provide a truck side frame which may be detachably connected to a journal box in a manner to obviate the use of bolts and whereby an emergency fastening is formed should the truck be 25 derailed or lifted from the track by any other part than the axles.

These and other objects are accomplished by means of the arrangement disclosed on 30 the accompanying sheet of drawings, in which—

Figure 1 is a fragmentary side elevation of my improved pedestal truck side frame, showing its means of attachment to a Master 35 Car Builders' standard journal box;

Fig. 2 is a top plan view of the same arrangement; and

Fig. 3 is an end view thereof.

The various novel features of my invention will be apparent from the following 40 description and drawings and will be particularly pointed out in the appended claims.

Referring to the figures of the drawings, it will be noted that I have provided a truck 45 side frame 10 having pedestal jaws 11, the lower ends of which terminate in laterally extending portions 12, which extend toward each other lengthwise of the side frame. These extending jaw portions 12 engage the 50 sides of the Master Car Builders' journal box 13 intermediate its ends, and more particularly intermediate the vertical planes of the journal box bolt lugs 14. As is apparent from the arrangement disclosed in the 55 figures of the drawings, it would be impos-

sible to apply the side frame to the journal box by a relative vertical movement while the jaw extensions 12 are intermediate the journal box bolt lugs 14. Accordingly, to apply the side frame to the journal box 60 when the latter is fixed on the journal, the side frame 10 is moved inwardly with respect to the journal box to a point where the relatively narrow jaw extensions 12 may pass vertically downwardly between the 65 inner journal box bolt lugs 14 and the dust guard housing 15. With the side frame in this position the same may be lowered, permitting the jaw extensions 12 to pass vertically downwardly beyond the upper journal 70 box bolt lugs 14, whereupon the side frame may be moved relatively outwardly with respect to the journal box to take its normal operating position. It will be noted that the side frame 10 is provided with four 75 housing lugs 16 which fit over the outside and embrace the four upper journal box bolt lugs 14. Accordingly, when the journal box 13 and side frame have been moved relatively laterally to a point where the 80 housing lug 16 may assume the proper position with respect to the box lugs 14, the side frame 10 is lowered into the position 85 shown in Fig. 1 of the drawings to prevent relative lateral movement between the side frame and journal box under normal operating conditions. It will be noted that the jaw extensions 12 are spaced from the housing lugs 16 vertically an amount to accommodate the box lugs 14 in applying the 90 frame to and withdrawing the same from the journal box. The pedestal jaw extensions 12 act as an emergency fastening for maintaining the connection between the side frame and the journal boxes, and therefore 95 the wheels and axles, in the event that the truck is derailed or is lifted from the track by any other part than the axles. It will be noted that no bolts or other fastenings of any kind are required to hold the side 100 frame in proper position other than the parts hereinabove specifically set forth, the housing lugs 16 embracing the sides of the journal box lugs 14 and the pedestal jaw extensions 12 bearing against the sides of 105 the box for holding the same in proper relation to the side frame. It will be understood that when it is desired to replace a broken journal box, the same may be done 110 by raising the side frame an amount to

properly accommodate the upper journal box lugs 14 between the jaw extensions 12 and the housing lugs 16, whereupon the new journal box may be moved laterally inwardly to the point where the housing lug 16 may move down over the journal box lugs 14.

It is my intention to cover all modifications of the invention falling within the 10 spirit and scope of the following claims.

I claim:

1. A pedestal truck side frame including open pedestal jaws having portions which embrace bolt lugs of Master Car Builders' journal boxes normally to prevent relative lateral movement between the side frame and journal box, said jaws terminating in inwardly extending portions for engaging the sides of the boxes for supporting same.
2. A pedestal truck side frame including open pedestal jaws having portions which engage bolt lugs on Master Car Builders' journal boxes normally to prevent lateral movement between the side frame and journal box, said jaws terminating in inwardly extending portions for engaging said bolt lugs to prevent accidental vertical separation of the boxes from the frame.
3. A pedestal truck side frame including

pedestal jaws having cooperating box receiving portions which may be applied to a Master Car Builders' journal box between the inner lugs on the latter and the dust guard housing whereupon the side frame 35 and journal box may be moved relatively to each other to their normal relative positions.

4. A pedestal truck side frame including pedestal jaws having portions which embrace bolt lugs of Master Car Builders' 40 journal boxes normally to prevent relative lateral movement between the side frame and journal box, said pedestal jaws also having portions which embrace the sides of the journal box between the bolt lugs thereof 45 for assisting in maintaining the operative position of said side frame and said journal box.

5. A pedestal truck side frame having open pedestal jaws and lugs spaced from 50 each other whereby a journal box having lugs may be applied by a lateral movement therebetween, said pedestal jaws normally embracing the sides of the journal box and said lugs embracing the journal box lugs for 55 preventing relative movement between the side frame and journal box.

Signed at St. Louis, Missouri, this 22nd day of December, 1919.

HARRY E. DOERR.
